FIG. 5

UNITED STATES PATENT OFFICE.

JOHN O. WISHART AND WILLIAM WISHART, OF CLINTON, IOWA, ASSIGNEES TO
CLINTON REFRIGERATING COMPANY, OF CLINTON, IOWA, A CORPORATION OF
IOWA.

COMPRESSOR.

1,360,611.

Specification of Letters Patent. Patented Nov. 30, 1920.

Application filed February 26, 1918. Serial No. 219,210.

To all whom it may concern:

Be it known that we, JOHN O. WISHART and WILLIAM WISHART, citizens of the United States, and residents of the city of Clinton, in the county of Clinton and State of Iowa, have invented certain new and useful Improvements in Compressors; and we do hereby declare that the following is a full, clear, and exact description of the 10 same, reference being had to the accompanying drawings, and to the numerals of reference marked thereon, which form a part of this specification.

This invention has reference more particularly to a compressor or pump for heavy duty such as in refrigerating plants and the like, and which is adapted to furnish a continuous supply of fluid under pressure.

An object of the invention is to provide 20 a compressor in a simple, compact form, so constructed that the parts thereof are easily accessible for removal and repairs.

Another object of the invention is to provide a compressor having reciprocating 25 compressing members with operating means whereby lateral strain on the reciprocating members is avoided.

Another object of the invention is to provide a compression cylinder which is open 30 at the intake end and provided with an enlarged suction chamber separated from the crank case of the compressor.

Another object of the invention is to provide a compressor having a separate suction 35 chamber for each cylinder apart from the crank case and a valved opening through the piston transmitting the fluid from the suction chamber to the compression chamber.

Another object of the invention is to provide a compressor having a crank case with an enlarged opening at each side thereof, and a cover for each of said openings whereby access may be had to the interior of the 45 crank case.

Another object of the invention is to provide a compression cylinder with a water jacket for the cylinder, formed by a removable shell which is readily detachable therefrom.

Another object of the invention is to provide a new valve construction to coöperate with the end of the cylinder for con-

trolling the discharge of compressed fluid therefrom.

55

Our invention also has other objects which will appear from the following specification and the accompanying drawings.

Our invention (in a preferred form) is illustrated in the accompanying drawings 60 and described in the following specification.

On the drawings:

Figure 1 is a side view of a compressor embodying our improvements.

Fig. 2 is a view of the compressor shown 65 in Fig. 1, looking at the left hand side thereof and having the fly wheel thereof removed on the line 2—2 of Fig. 1.

Fig. 3 is an enlarged sectional view on the line 3—3 of Fig. 2, parts thereof being 70 shown in elevation.

Fig. 4 is a vertical sectional view on the line 4—4 of Fig. 3, parts thereof being shown in elevation.

Fig. 5 is a horizontal sectional view on the 75 line 5—5 of Fig. 3, parts thereof being shown in plan.

Fig. 6 is an enlarged vertical sectional view of the upper end of one of the cylinders.

80

Fig. 7 is a transverse sectional view on the line 7—7 of Fig. 6.

Fig. 8 is an enlarged vertical sectional view of the piston.

Fig. 9 is a view on line 9—9 of Fig. 8. 85

Fig. 10 is a sectional view on line 10—10 of Fig. 8.

As shown on the drawings:

The reference numeral 1, indicates the base of the compressor which has the elevated top 2, upon which the crank case 3 is secured by means of the bolts 4, which are passed through a flange 5, extending around the bottom of the crank case. The bolts 4, are threaded into the top 2. At each side 95 of the crank case is an opening 6, which is closed by a cover 7, secured in place by means of the bolts 8, so that access may be had to the interior of the crank case.

The compressor herein shown is of the 100 type having a pair of adjacently disposed parallel cylinders. The top of the crank case is provided with a pair of openings to receive the lower ends of a pair of cylinder supports 9, each of which is provided with 105 an annular flange 10, adjacent the lower

end thereof adapted to rest upon the upper surface of the crank case 3, and be secured thereon in position by means of the bolts 11. Mounted on the upper end of each cylinder support 9, is a cylinder 12, which closes the upper end of the cylinder support 9, and has the lower end therein projecting into the cylinder support 9. An annular flange 13, is integrally formed on the cylinder 12, intermediate of the ends of the cylinder, and said flange 13, engages the upper end of the cylinder support 9, and is secured thereto by the bolts 14. Packing 15, is interposed between the flange 13, and the upper end of the cylinder support 9, to insure a tight joint.

Mounted to reciprocate in each cylinder 12, is a hollow piston 16, which has the usual piston rings 17, seated annularly in the grooved outer surface thereof to engage the bore of the cylinder 12, and make a fluid tight sliding joint. At the lower end thereof, the piston has a spider 18, with a central hub 19, to which the piston rod 20, is secured, said spider comprising radial arms, connecting the hub with the piston wall whereby passages are provided through the piston.

The piston rod 20, extends down into the crank case 3, to be operated by the crank shaft 21, journaled therein. The lower end of the cylinder support 9, is closed by a bottom to provide a fluid suction chamber 22, at the lower end of the cylinder. The bottom of the cylinder support has an opening therethrough through which the piston rod 20, is passed. In order to prevent leakage around the piston rod 20, from the chamber 22, to the crank case 3, the bottom of the cylinder support 9, has a sleeve 23, embracing the piston rod 20, and provided with an elongated packing chamber 24, in which packing 25, is placed and compressed. A bushing 26, is adapted to slide in the lower end of the packing chamber 24, to compress the packing 25, therein and pressure is applied to this bushing, by means of the internally threaded nut 27, which engages the external threads on the lower end of the sleeve 23, and bears against the outer end of the bushing 26.

For supporting the crankshaft 21, in the crank case 3, the crank case is provided at opposite sides with the journal boxes 28 and 39 which are detachably connected with the side walls of the crank case by means of the bolts 29 and 37 respectively, and have the bearings 30, inserted therein which directly engage the shaft 21, to receive the wear thereof, which construction enables the journal boxes 28 and 39, to be easily removed and the bearing insert 30, conveniently replaced. The crank shaft 21, is provided in the crank case 3, intermediate the bearings 28 and 39, with a pair of diametrically op-

posed cranks having the crank pins 31, properly positioned to operate the piston rods 20, and there is a fly wheel 32, on the crank shaft 21, at the outside of the crank case whereby the crank shaft is operated to drive 70 the pistons.

In order that the crank shaft may be readily removed from the crank case, there is at one side of the crank case an elongated opening 33, in the upper end of which the journal box 39, is located and there is a plate 34, closing this opening which is secured to the crank case by means of the bolts 35. The journal box 39, at that side of the crank case is inserted through the opening 36, in the 80 plate 34, and is secured to said plate 34, by means of the bolts 37. In order to insure accurate placing of the journal box 39, the upper bolts 37, are passed entirely through the plate 34, and threaded into the crank 85 case 3, as shown in Fig. 3.

It is essential that the bearings 30, be placed in position so that proper alinement is assured for operation of the crank shaft 21, therein, and for this purpose the openings in the crank case and plate 34, are carefully alined and the journal boxes are each provided with a turned shoulder which fits in the respective opening and holds the bearings in proper alinement. As a further 95 means to facilitate proper placing of the bearings there is a raised rim or boss around the outer edge of each journal box opening in the crank case. The plate 34, which is milled is adapted to be held against one of 100 said raised rims by the flange 86, of the journal box 39, by means of the attaching bolts 37, while the flange 86, of the journal box 28, is held against the other raised rim by the bolts 29.

Each piston rod 20, is secured at its lower end to a cross head 40, which comprises a pair of transverse guides 41, which are secured together by a bolt 42, at each end and properly spaced by means of sleeves 43, on 110 the bolts between the guides 41. Each cross head 40, embraces one of the crank pins 31, of the crank shaft and there is a journal box on each crank pin consisting of the two half sections 44, which fit between and are held 115 together by means of the guides 41, and are adapted to slide lengthwise of the said guides, and are confined on the guides by means of the lips 45, which engage the edges of the guides 41. To provide for the wear 120 occasioned by the operation of the crank pin 31, in the journal box sections 44, a bearing 46, is interposed between the crank pin 31, and the journal box, which bearing can be removed and replaced when necessary. The 125 operation of the cranks by reason of their engagement with the cross heads 40 is adapted to reciprocate the piston rods 20. To hold the piston rods against lateral strain, there is a rod 47, extended from the bottom 130

- of each of the lower cross head guides 41, in alinement with the respective piston rod 20, and said rod 47, slides in a guide bearing 48, in the top 2, of the base 1.
- 5 From the foregoing, it will be apparent that as the crank shaft 21, is operated, the crank pins 31, are caused to travel in a circular path and impart a corresponding movement to the journal boxes 44. The journal boxes 44, however being adapted to slide laterally, and the cross heads being incapable of lateral movement, the sidewise movement of the crank pins 31, will impart a lateral movement, to the journal boxes 44, 10 in the cross heads 40, and only the vertical movement of the crank pins will be applied to the cross heads 40, and the piston rods 20, so as to operate the piston 16, on the upper ends thereof.
- 15 20 The upper end of the cylinder 12, is closed by means of the cylinder head 49, which is secured to the upper end of the cylinder by means of the bolts 50. There is a valve holder 51, in the upper end of the cylinder 25 at the inside of the cylinder head 49, which supports the spring pressed valve 52, for closing the upper end of the cylinder. This valve holder 51, is held in place by means of an annular flange 53, thereof, which seats 30 against the flange 54, at the upper end of the cylinder and is clamped thereagainst by means of the cylinder head 49, bearing against the upper surface of the flange 53. There is a disk 55 formed on the lower end 35 of the valve holder 51 adjacent the upper end of the cylinder bore, and the valve 52, covers the lower face of the disk 55, and has an upturned flange 56, which engages the rim of the disk 55. The central portion 40 of the valve holder 51, has a vertical opening 59, therein and a hub 57, formed on the upper face of the valve 52, slides in said opening and has the stem 58, thereof projecting up through the end wall of said 45 opening 59. The spring 60 is coiled around the stem and compressed between the hub 57, of the valve and the end wall of the opening 59, so as to force the valve against the valve seat 61, provided therefor in the 50 upper end of the cylinder whereby the upper end of the cylinder piston bore is normally closed.
- 55 It will be noted that by reason of the disk 55, fitting within the annular flange 56, of the valve 52, a closed compartment is formed between the disk 55, and the valve 52, when the valve is closed against the seat 61, and to provide relief from this compartment and prevent compression or 60 vacuity in the compartment which would interfere with the operation of the valve 52, there is an opening 62 (see Fig. 4) through the flange 56, communicating with the space between the disk 55, and the 65 valve 52.
- The fluid to be compressed is introduced into the suction compartment 22, at the lower end of the cylinder through the inlet pipe 63, and is discharged from the compression chamber at the upper end of the cylinder through the outlet pipe 64, and passes from the suction chamber 22, through the piston into the upper end of the cylinder and is from there forced through the valve 52, into the chamber 65, at the upper 70 end of the cylinder which chamber communicates with the pipe 64.
- In order to permit easy passage of the fluid through the piston and close the upper end of the piston, when it is acting to compress the fluid in the upper end of the cylinder, a valve ring 66, is threaded into the upper end of the piston 16, and provided with a valve seat 67, and upwardly opening valve 68, which when seated, together with 80 the ring 66, effectively closes the upper end of the piston. A hub 69, is connected by means of the spider 70, to the valve ring 66, and spaced therefrom, so as to provide a guide for the stem 71, to which the valve 68, 90 is attached. The lower end of the stem 71, has a head 72, spaced from the hub 69, and there is a spring 73, coiled about the stem 72, and compressed between the head 71, and the hub 69, to hold the valve 68, against the 95 seat 66. There is also another spring 74, coiled about the stem 71, and compressed between the hub 69, and the valve 68, the purpose of which is to balance the tension of the spring 73, and hold the valve 68, 100 lightly closed so that it will readily open when the piston is moved downwardly, and admit fluid therethrough to the chamber in the cylinder above the piston.
- A water jacket is provided for the upper 105 end of the cylinder and consists of a shell 75, which is of sufficient diameter to telescope over the upper end of the cylinder and has the lower edge thereof seated in an annular groove 76, formed in the upper end of 110 the cylinder support 9. A threaded stem 77, projects from the top of the cylinder head 49, and is inserted through an opening in the upper end of the cylinder jacket 75, and has the nut 78, threaded thereon against 115 the top of the water jacket shell 75 to clamp it down into the grooves 76. This groove may be provided with a packing material to prevent leakage. Suitable water pipes 80 and 81 are connected with the water 120 jacket 75, to supply and remove water therefrom for cooling the cylinder. The outlet pipe 64, from the compressor is passed through the water jacket 75, and there is a boss 82, on the water jacket 75, surrounding the pipe 64, which is internally threaded to receive the nut 83, which is adapted to compress a ring of packing material 84, in the boss 82, around the pipe 64, to prevent leakage. One of the pipes 80 and 81 is con- 125 130

nected with a source of water supply to circulate water in the jacket 75, around the cylinder 12. The pipe 63, is connected to the supply of fluid to be compressed, and the pipe 64, is connected to transmit the compressed fluid to the desired point.

The crank shaft 21, is rotated by means of power applied to drive wheel 32, and by reason of the connection of the crank pin 31, with the cross head 40, imparts a reciprocating movement to the piston rod 20, and the piston 16, at the upper end thereof. Owing to the fact that valve 68, is normally closed, the upward movement of the piston draws in a supply of fluid to be compressed through the pipe 63, into the suction chamber 22. The valve 52, at the upper end of the cylinder, being normally closed, when the piston 16, moves downwardly at the end of its upward stroke, a partial vacuum is formed in the cylinder above the piston and inasmuch as the valve 68, is lightly closed by reason of the balanced tension of the springs 74, and 73, this valve readily opens, and a supply of fluid to be compressed is admitted into the cylinder above the piston. As a further means of admitting fluid to the cylinder above the piston so as to insure the chamber being completely filled, I have provided a port 79 (see Fig. 4) in the wall of the cylinder which affords communication between the suction chamber 22 and the compression chamber of the cylinder when the piston is in the lowermost position and which is closed by the piston as it starts to move upwardly. When the piston starts to move upwardly at the end of the downward stroke, the valve 68, immediately closes and further upward movement compreses the fluid in the chamber above the piston until it reaches a degree of compression sufficient to overcome the tension of the spring 60, and the pressure within the chamber 65, whereupon the valve 52, will be raised and the contents of the cylinder forced into the chamber 65, and out through the pipe 64.

For the purpose of illustration, we have shown our invention embodied in a certain form, and we are aware that various changes may be made and details of construction varied through a wide range without departing from the principles of this invention. We therefore do not purpose limiting the patent granted otherwise than necessitated by the prior art.

We claim as our invention:

1. In a compressor, the combination of a crank case, a crank shaft in the crank case, and a removable journal box at each side of the

crank case for the crank shaft, and a removable elongated plate at one side of the crank case coöoperating with one of the journal boxes to admit the crank shaft to the interior of the crank case.

65

2. In a compressor, the combination of a cylinder, having an annular valve seat at one end, a cylinder head secured to the end of the cylinder, a removable valve holder intermediate of the cylinder head and valve seat, a disk on the holder adjacent the valve seat, a valve on the holder intermediate of the disk and valve seat, and means on the valve holder for resiliently holding the valve against the seat.

75

3. In a compressor the combination of a crank case and cylinder, a piston in the cylinder, a crank shaft in the crank case, said crank case having a large opening in one side thereof for inserting the crank shaft therein, a plate for closing said large opening, said plate and the opposite side of the crank case having bearing openings therein, removable bearing for the crank shaft in each of said openings, and means for holding said bearings in relative alinement.

85

4. The combination with a compressor, of a cylinder having a valve seat at one end thereof, a cylinder head removably secured on the cylinder, a valve holder removably secured between the cylinder and said cylinder head, a disk formed on said holder, and a valve supported by the holder and disposed between the valve seat and said disk for normally closing the cylinder.

95

5. The combination with a compressor, of a cylinder having a valve seat near one end thereof, a valve holder on the upper end of the cylinder and projecting thereinto, a disk on the inner end of said holder spaced from the cylinder valve seat, a valve carried by said holder between said disk and valve seat for normally closing the cylinder, a cylinder head for holding the holder secured in place, a stem integrally formed on said head, an apertured water jacket surrounding the cylinder and the cylinder head with the stem projecting through the aperture in said water jacket, and means removably engaged on the stem to hold the water jacket secured in position.
